UNITED STATES PATENT OFFICE.

ALFRED STROMBERG, OF CHICAGO, ILLINOIS.

TELEPHONE-TRANSMITTER.

SPECIFICATION forming part of Letters Patent No. 643,830, dated February 20, 1900.

Application filed November 10, 1899. Serial No. 736,475. (No model.)

To all whom it may concern:

Be it known that I, ALFRED STROMBERG, a citizen of the United States, residing at Chicago, in the county of Cook and State of Illinois, have invented a certain new and useful improvement in Telephone - Transmitters, (Case No. 2,) of which the following is a full, clear, concise, and exact description, reference being had to the accompanying drawings, forming a part of this specification.

My invention relates to telephonic apparatus, and has for its object the construction of an improved form of transmitter which is adapted by varying the resistance of a transmitter-circuit, including a battery, to propagate voice-currents to suitable receivers.

My invention has for one object the construction of an improved battery-transmitter which, while depending for its operation upon variation of resistance in the circuit including the same occasioned by sound-waves, does not depend upon variation in pressure between electrodes included in the transmitter-circuit.

To this end my invention in its preferred embodiment comprises a movable element or electrode adapted to be actuated by sound-waves, the movement of this element being so controlled that while it is adapted to vary its position with relation to the engaging electrode it in no wise exerts a varying pressure upon nor displaces the same.

My invention in its preferred embodiment comprises a revoluble electrode having a fixed axis of rotation and arranged to be rotated upon its axis by means of sound-waves, a second electrode being in engagement therewith, the area of contact between the electrodes being varied by the movement of the revoluble electrode. In practice I preferably employ as the electrode for engaging the revoluble electrode granulated carbon particles.

As is well known to those skilled in the art, louder sounds occasion increased pressure between transmitter-electrodes of the battery-transmitter now commonly used, thereby reducing the resistance of the transmitter-circuit, and fainter sounds, by causing a lesser pressure between the electrodes, would result in a relatively-greater resistance of the transmitter-circuit. Fainter sounds therefore have less current to cause the propagation of elec-

trical undulations similar in form to the sound-waves than the louder sounds.

My invention has for another of its objects the provision of a transmitter wherein the fainter sounds are accompanied by lower resistance in the transmitter-circuit than the louder sounds. I am enabled to accomplish this result by employing a transmitter that does not vary the pressure between its electrodes, the preferred embodiment of my invention that I have above set forth being admirably adapted to carry out this second feature of my invention.

I will describe my invention more particularly by reference to the accompanying drawings, illustrating the preferred embodiment thereof, in which—

Figure 1 is a plan view of my improved transmitter suitably supported in place. Fig. 2 is a side view of the apparatus shown in Fig. 1. Fig. 3 is a longitudinal elevation of the transmitter. Fig. 4 is a view in cross-section of the transmitter on line 4 4 of Fig. 1, circuit connections of the transmitter being indicated diagrammatically. Fig. 5 is a longitudinal sectional elevation on line 5 5 of Fig. 1. Fig. 6 is a view of the revoluble electrode separated from its supporting-shaft. Fig. 7 is a plan view of the receptacle for containing the comminuted electrode, the revoluble electrode being removed.

Like parts are indicated by similar letters of reference throughout the different views.

In practicing my invention I take pains to prevent variation in pressure between electrodes of the transmitter-circuit, and the construction illustrated is well adapted to this end. One of the electrodes is preferably in the form of carbon granules *a*, held in place by a suitable packing *b*, preferably formed of plush, the plush packing surrounding the carbon granules upon four sides, the carbon being preferably inclosed in a rectangular space. A support *c* is rigidly secured in position upon the brace-piece *d* or other suitable mounting, the plush packing being glued in place within the cavity of this support, as shown most clearly in Figs. 4 and 5. The portion of the support holding the carbon is metallic, the carbon granules being in direct electrical contact therewith. The support is

preferably extended longitudinally in both directions from the carbon electrode and is provided with a binding-screw or other suitable means for connecting a transmitter-conductor therewith, whereby said carbon is made to constitute an electrode. Insulating-plates *g* are rigidly secured to the ends of the support *c*, each plate supporting a bearing-screw *h*, projecting inwardly. A shaft *i* is journaled at its ends upon the screws *h h*, this shaft supporting a cylinder formed in sections of metal and insulating material, one half of the cylinder *k* being preferably formed of insulating fiber, while the other half *l* is preferably formed of brass. These parts of the cylinder may be suitably secured together upon the shaft by means of screws. The metal member *l* is preferably gold-plated. This composite cylinder is preferably so disposed that the metal and insulating portions thereof are both normally in contact with the carbon granules or other comminuted material, the plush packing employed to confine the carbon in place surrounding the lower portion of the cylinder to retain the carbon in uniform contact with the cylinder as a whole. I have shown a flexible wire *m* attached to the shaft of the cylinder, the shaft being in metallic contact with the part *l*.

30 One of several transmitter-circuits that may be employed in connection with my invention is illustrated in Fig. 4, where one terminal of the battery *n* is connected with the support *c* and the carbon *a*, while the other terminal of the battery is adapted to be united with the metallic portion *l*, a primary coil *o* being adapted for connection between the battery and the part *l*. A secondary *p* is shown in circuit with the receiver *q*, a switch-hook *r* serving to include both limbs *s* of a telephone-line extending to an exchange, for example, in circuit with the secondary coil and the receiver when the receiver is removed from the switch-hook. The switch-hook also serves to close the transmitter-circuit when the receiver is removed. I preferably actuate the revoluble electrode by the mechanism illustrated. I employ a diaphragm *t*, located at the rear of a mouth-piece *u*, and arm *v* being secured, preferably, to the central portion of the diaphragm at one end, this arm being provided with a recess or aperture at its other end, which receives the sharp point of a pin *w*, extending radially from the shaft *i*, this pin serving the function of a crank, as will be more readily understood by reference to Fig. 4. A movement of the diaphragm is accompanied by a longitudinal motion of the arm or link *v*, which in turn, by its engagement with the pin *w*, will cause a rotation of the cylinder. When the arm is pressed in by the action of the sound-waves, the composite cylinder will be rotated in a clockwise direction, thereby decreasing the area of contact between the metallic portion *l* of the cylinder and the carbon or other comminuted material engaging

the same, whereby the resistance of the circuit including the battery *n* is increased. When the diaphragm is restored to its initial position, the area of contact between the electrode *l* and the comminuted carbon electrode is increased to decrease the resistance in the transmitter-circuit. Fainter sounds are therefore accompanied by lower resistance in the transmitter-circuit than the louder sounds. While the resistance of the transmitter-circuit is increased upon an increase of force in the sound-waves, sufficient of the carbon is always maintained in contact with the part *l* to prevent the resistance from being too great for the proper operation of the transmitter.

While I have herein shown a well-known transmitter-circuit and have illustrated the preferred embodiment of my invention in connection therewith, it is obvious that changes may readily be made without departing from the spirit of my invention, and I do not therefore wish to be limited to the precise construction and arrangement shown nor to the use of comminuted carbon as an electrode. I am enabled by means of my invention to overcome serious objections heretofore existing against transmitters employing comminuted material as an electrode. Heretofore the comminuted electrode was liable to pack, especially where carbon was employed. Moreover, it was difficult to secure and maintain proper relative adjustment between the diaphragm and the comminuted electrode. Accidental buckling of the diaphragm in transmitters of this class and in variable-pressure transmitters was very liable to throw the transmitter out of adjustment. By means of the transmitter of my invention it is not necessary to secure and maintain any particular adjustment of the transmitter.

While I have shown the comminuted electrode as being stationary and the electrode engaging the same as being revolvable, I do not wish to be limited to the precise structure shown nor to the employment of a local transmitter-circuit.

Having thus described my invention, I claim as new and desire to secure by Letters Patent—

1. In a telephonic transmitter adapted for operation by sound-waves, the combination with two electrodes adapted for inclusion in a transmitter-circuit, of means for varying the contact between the electrodes without varying the pressure between the electrodes to increase the resistance of the transmitter-circuit upon an increase in force of the sound-waves, and to cause a relatively-less resistance in the transmitter-circuit upon a decrease in the force of the sound-waves, substantially as described.

2. The combination with a transmitter-circuit including a battery and engaging electrodes of a transmitter, of means for decreasing the area of contact between the electrodes of the transmitter upon an increase in the

force of the sound-waves, and for effecting a relative increase of the area of contact between the electrodes upon a decrease in the force of the sound-waves without varying the pressure between the electrodes, substantially as described.

3. In a telephonic transmitter, the combination with a revoluble electrode, of a second electrode in contact therewith, and means for effecting the rotation of the revoluble electrode through the agency of sound-waves without varying the pressure between the electrodes, substantially as described.

4. In a telephonic transmitter, the combination with a revoluble electrode, of a second electrode in contact therewith, a diaphragm, and a connection between the diaphragm and the revoluble electrode to effect the rotation thereof through the action of sound-waves without varying the pressure between the electrodes, substantially as described.

5. In a telephonic transmitter, the combination with a revoluble electrode, of a second electrode in contact therewith, the said revoluble electrode being confined to a fixed axis of rotation, a diaphragm, and a connection between the diaphragm and the revoluble electrode to effect the rotation thereof through the action of sound-waves, substantially as described.

6. In a telephonic transmitter, the combination with a revoluble electrode, of a second electrode in contact therewith, a diaphragm, an arm *v* engaged between the diaphragm and the revoluble electrode serving to vary contact between said electrodes without varying the pressure between them, whereby upon an actuation of the diaphragm, the revoluble electrode is actuated to vary the resistance in the transmitter-circuit, substantially as described.

7. In a telephonic transmitter, the combination with a revoluble element formed in sections of metal and insulating material, of a second electrode adapted for engagement with the said metal and insulating material, the metal constituting an electrode of the transmitter, and means for effecting the rotation of the said element to vary the area of contact between the revoluble electrode and the electrode engaging the same, substantially as described.

8. In a telephonic transmitter the combination with a revoluble element formed in sections of metal and insulating material, of a second electrode adapted for engagement with the said metal and insulating material, the metal constituting an electrode of the transmitter, and means for rotating the element to decrease the area of contact between the revoluble electrode and the engaging electrode upon an increase in the force of the sound-waves, and to effect a relative increase of the area of contact upon a decrease in the force of the sound-waves, substantially as described.

9. In a telephonic transmitter, the combi-

nation with a revoluble element formed in sections of metal and insulating material, of a second electrode adapted for engagement with the said metal and insulating material, the metal constituting an electrode of the transmitter, a diaphragm, and a connection between the diaphragm and the said revoluble element for effecting its rotation, substantially as described.

10. In a telephonic transmitter, the combination with a revoluble element formed in sections of metal and insulating material, of a second electrode adapted for engagement with the said metal and insulating material, the metal constituting an electrode of the transmitter, a diaphragm, an arm *v* interposed between the diaphragm and the revoluble element, and a pin *w* provided upon the revoluble element and engaging the contiguous end of the arm *v*, substantially as described.

11. In a telephonic transmitter, the combination with an electrode in the form of comminuted material, of a revoluble element having uniform engagement with the said comminuted material, a packing for securing the comminuted material in place, the said revoluble element comprising a portion of insulating material and a metal portion, both adapted for engagement with the comminuted material, the said metallic portion constituting the other electrode of the transmitter, and means for effecting a rotation of the said element to vary the area of contact between the revoluble electrode and the comminuted material, substantially as described.

12. In a telephonic transmitter, the combination with an electrode in the form of comminuted material, of a revoluble element having uniform engagement with the said comminuted material, a packing for securing the comminuted material in place, the said revoluble element comprising a portion of insulating material and a metallic portion, both adapted for engagement with the comminuted material, the said metallic portion constituting the other electrode of the transmitter, and means for decreasing the area of contact between the revoluble electrode and the comminuted material upon an increase in the force of the sound-waves and for effecting a relative increase of the area of contact between the revoluble electrode and the comminuted material upon a decrease in the force of the sound-waves, substantially as described.

13. In a telephonic transmitter the combination with an electrode in the form of comminuted material, of a revoluble element having uniform engagement with the said comminuted material, a packing for securing the comminuted material in place, the said revoluble element comprising a portion of insulating material and a metal portion, both adapted for engagement with the comminuted material, the said metallic portion constituting the other electrode of the transmitter, a

diaphragm, a pin *w* extending from the shaft of the revoluble element, and an arm *v* interposed between the diaphragm and the said pin, substantially as described.

- 5 14. In a telephonic transmitter, the combination with an electrode in the form of comminuted material, of a revoluble element having uniform engagement with the said comminuted material, a packing for securing the comminuted material, in place, the said revoluble element comprising a portion of insulating material and a metallic portion, both adapted for engagement with the comminuted material, the said metallic portion 15 constituting the other electrode of the transmitter, a diaphragm, and an arm *v* interposed between the diaphragm and the revoluble element to effect the rotation thereof, substantially as described.
- 20 15. In a telephonic transmitter, the combination with an electrode in the form of comminuted material, of a revoluble element having uniform engagement with the said comminuted material, a packing for securing 25 the comminuted material in place, the said revoluble element comprising a portion of insulating material and a metallic portion, both adapted for engagement with the comminuted material, the said metallic portion 30 constituting the other electrode of the transmitter, a diaphragm, and an arm *v* interposed between the diaphragm and the revoluble element to effect the rotation thereof, the arm *v* being so disposed with relation to 35 the revoluble element as to decrease the area of contact between the revoluble electrode and the comminuted material upon an increase of force in the sound-waves, and to

effect a relative increase of the area of contact between the revoluble electrode and the 40 comminuted material upon a decrease in the force of the sound-waves, substantially as described.

16. In a telephone-transmitter, the combination with an electrode, of a second comminuted electrode and means for effecting the rotation of one of the electrodes through the agency of sound-waves, substantially as described.

17. In a telephone-transmitter, the combination with an element formed in sections of metal and insulating material, the metal constituting an electrode of the transmitter of a second comminuted electrode in engagement with the metal and insulating portions 55 of the aforesaid element, and means for effecting the rotation of one of the electrodes through the agency of sound-waves, substantially as described.

18. The combination with a transmitter-60 circuit including a battery and the electrodes of a transmitter which have sliding contact in the operation of the transmitter, of means for decreasing the area of contact between the electrodes of the transmitter upon an increase in the force of the sound-waves and for effecting a relative increase of the area of contact between the electrodes upon a decrease in the force of the sound-waves, substantially as described.

In witness whereof I hereunto subscribe my name this 8th day of November, A. D. 1899.

ALFRED STROMBERG.
